UNITED STATES PATENT OFFICE.

SIDNEY McCLOUD, OF CHICAGO, ILLINOIS.

METALLIC RAILWAY-TIE.

949,834.

Specification of Letters Patent. Patented Feb. 22, 1910.

Application filed May 24, 1909. Serial No. 497,985.

To all whom it may concern:

Be it known that I, SIDNEY McCLOUD, a citizen of the United States, residing at Chicago, Illinois, have invented certain new and 5 useful Improvements in Metallic Railway-Ties, of which the following, taken in connection with the drawings, is a description.

My invention has for its object the production of a metallic railway tie, one which is an 10 embodiment of strength, durability and efficiency, and is so constructed that it is capable of being placed on the market at a much lower cost than is possible with metal ties now commonly known, the excessive price 15 having heretofore been a serious obstacle in the way of the general use of ties of this class.

A further object of the invention is to produce a tie which shall have sufficient spring 20 or resiliency to withstand the jars and strains caused by moving trains, without overtaxing the tie and cracking or disrupting the metal.

Still a further object is to provide a new 25 and useful means for securing the rail to the supporting member, bracing it, and preventing any possibility of tip, slip or sidewise displacement. And yet a further object of the invention is to provide a tie which may 30 readily be disposed in the road bed, evened up and tamped with the ballast to securely hold it in place, provision also being made against endwise movement.

In the accompanying drawings I have 35 illustrated the best embodiments of my invention now known to me, premising, however, that various modifications in detail, and touching the arrangement and construction of the different parts, will suggest themselves 40 to persons skilled in the art relating to this class of devices, and in these drawings—

Figure 1 is a top plan view of the preferred form of my invention; Fig. 2 is a 45 longitudinal sectional view taken upon the corresponding numbered line in the preceding figure; Fig. 3 is an enlarged sectional detail showing a brace and fastening for the rail, together with the rail and the top plate of the rail supporting member, all in assembled position; Fig. 4 is a fragmentary view, 50 taken on line 4—4 of Fig. 2, showing a portion of a rail in elevation, an end view of the rail supporting member, and a transverse sectional view through the trough of the tie in collocation; Fig. 5 is a view, similar to the preceding, of a modified form of

construction, and Fig. 6 is a perspective view of the preferred form of rail supporting member.

In carrying out the invention the tie is 60 formed or built up channeled or tray-shaped, preferably from two oppositely facing angle irons A, A, the ends a, a of which are closed by being bent inwardly toward each other and overlapped, as shown in Figs. 1 and 2, 65 this construction forming an elongated channel or trough the bottom of which is intended to rest upon the graded road bed. The rail supporting members B, B, are arranged or disposed in this trough a suitable 70 distance apart, with proper relation to the ends of said trough, and are seated between snugs a', a', formed by looping, bending or striking inward the vertical flanges of the angle irons, as indicated in Fig. 1. 75

Secured to the bottom of the tie, at points directly beneath the rails B', B', by bolts or rivets b'' are anchor plates b, b which have downwardly projecting sides, anchors or lips b', b' preferably flaring in the direction of 80 the length of the tie, which extend into the road bed to provide additional gripping surfaces and further prevent or resist any endwise movement or slip of the tie. While these plates are desirable they are not indispensable to the successful use of my invention, and I contemplate constructing the tie 85 with or without said plates.

The bottom flanges of the angle irons forming the tie are recessed or cut away at 90 approximately the center of said tie, as at a², to form an elongated opening which provides sufficient drainage for the trough, allows the ballast to move through the tie with the weight of the traffic passing over it, 95 by reason of which the tie is prevented from bending upward in the middle on account of the more direct weight upon the outer ends than in the center, and affords additional security against endwise slip. 100

The rail supporting members B are formed separately from the trough of the tie, as already indicated, are disposed transversely in said trough, and provide a resilient base upon which the rails rest. 105 These members are each formed of a single piece of material, as shown more clearly in Fig. 4, bent into practically a tri-triangular shape and suitably tempered, the center triangle b² being secured at its base to the bottom of the trough by suitable fastenings, 110 which may be the same bolts or rivets b''

by which the anchoring plates b , b , are secured.

Between the bottom of the trough and the outer sides of the triangles b^3 , b^4 of the rail supporting members is a space b^4 extending the length of the supporting members. This space allows springing or flexibility of the outer triangles, permitting a practically vertical movement of the supporting member for automatic adjustment of the tie with respect to the road bed as the weight of the trains on the rails passes over it.

Formed upon the top or chair of the rail supporting members B , preferably integrally therewith, are the lugs or keepers c , c , against which the outer flange c' of the rail abuts. The rail is held in position against these lugs by clips c^2 , c^2 , taking over the inner flange and bolted to the top of the supporting member. For curves the lugs c , c , may be replaced by a higher lug B^2 projecting above the outer flange of the rail, as indicated in Fig. 3, where it is shown as formed upon the top of the supporting member and abutting against said outer flange. A brace C extends from the chin or re-entrant angle of the rail head down to the outer flange, then is bent to sit against and saddle lug B^2 , and finally is secured by bolts C' passing through its flanged end and the top of the supporting member. This makes a very reliable prop to prevent tipping or slewing of the rail as a train swings around a curve, but is not particularly necessary on straight lines.

In Fig. 5 is shown a modified or alternative form of the rail supporting member, in which the triangular base D has the ends d , d bent outwardly and horizontally to form the chair for the rail. In this construction the side walls of the trough member of the tie are bent inwardly to closely embrace the triangular body of the rail supporting member and the rail is secured to the latter by clips d' and bolts d^2 as shown.

I claim:

1. A metal tie or sleeper comprising two oppositely facing angle irons secured together to form a trough, rail supporting members in said trough, the sides thereof abutting against the vertical flanges of the angles, said vertical flanges of the angles being bent inwardly to form abutments at each end of the rail supporting members.

2. A metal tie or sleeper comprising two oppositely facing angle irons arranged to form a trough, resilient rail supporting members in said trough, said members abutting against the vertical flanges of the angles, and inwardly bent snugs in the vertical flanges of the angles providing abutments against lateral movement of the rail supporting members.

3. A metal tie or sleeper comprising two

oppositely facing angle irons arranged to form a trough, rail supporting members carried by said trough member, and plates secured to the bottom flanges of the irons, said plates having anchor lips flaring downwardly and outwardly in the direction of the length of the tie.

4. A metal tie or sleeper comprising two oppositely facing angle irons arranged to form a trough having an elongated central opening through the bottom thereof, resilient rail supporting members in said trough, a lug formed on the chair of each rail supporting member, said rail supporting members being secured to the bottom of the trough, the sides thereof abutting against the vertical flanges of the angles, and inwardly bent snugs on the vertical flanges of the angles providing abutments against lateral movement of the rail supporting members.

5. A metal tie or sleeper comprising oppositely facing angle irons arranged to form a trough, resilient rail supporting members secured inside the trough, lugs formed on said supporting members, and means co-acting with said lugs for securing rails to the supporting members.

6. A metal tie or sleeper comprising oppositely facing angle irons arranged to form a trough, resilient rail-supporting members secured in said trough, anchor-plates beneath the bottom flanges of the irons and secured thereto with the rail supporting members, and means for securing the rails to the supporting members.

7. A metallic tie comprising a trough or channel having an elongated opening through the center of its bottom, resilient rail supporting members in said trough, lugs formed on each of said members against which the flange of the rail abuts, and means for bracing the rail at the outside thereof against the supporting members.

8. A metallic tie comprising a trough or channel, resilient rail supporting members secured in said trough, a lug formed on the top of each supporting member, and a brace taking over said lug, abutting against the outer flange of the rail and extending to the reentrant angle of the head.

9. A metallic tie comprising a trough, resilient rail supporting members secured in said trough, a lug formed on the top or chair of each rail supporting member, and a brace secured to said chair at its foot, taking snugly over the lug, abutting upon the outer flange of the rail and extending to the reentrant angle of the head.

10. A metallic tie comprising a trough closed at each end, tri-triangular shaped rail supporting members disposed transversely of said trough and secured thereto, and means for securing rails to said supporting members.

11. A metallic tie comprising a trough closed at each end and having a central opening in the bottom, tri-triangular shaped supporting members disposed transversely of said trough and secured thereto, and means for securing rails to said supporting members.

12. A metallic tie comprising a trough closed at each end, resilient tri-triangular shaped rail supporting members disposed transversely of said trough and secured thereto, and means for securing rails to said supporting members.

13. A metallic tie comprising a channel shaped base, rail supporting members secured in said base, each of said rail supporting members comprising a single plate bent into tri-triangular shape, the outer ends thereof being of less height than the rail supporting member whereby vertical re-

siliency of said supporting member is obtained.

14. A metallic tie comprising a channel shaped base having an elongated opening in the center of the bottom thereof, rail supporting members each of which comprises a single plate formed into tri-triangular shape, the base of the center triangle being rigidly secured to the bottom of the channel, and the outer sides of the outer triangles being of less height than the rail supporting members whereby vertical resiliency of said supporting members is obtained.

In testimony whereof I have signed this specification in the presence of two subscribing witnesses.

SIDNEY McCLOUD.
